SNOWPLOW

Frank M. Becker, Sinking Spring, Pa.

Application March 15, 1950, Serial No. 149,791

4 Claims. (Cl. 37—12)

1

This invention relates to a snow-removal machine.

This invention is an improvement over my Snow Plow, Patent No. 1,705,389, dated March 12, 1929.

The object of the invention is to provide a machine which, moved along a street or roadway covered with snow and ice, will effectively remove or clear the snow and ice from the street or roadway.

Another object of the invention is to provide a snow-removal machine which includes a mechanism for scooping and breaking up the snow and ice, the machine including conveyors for receiving the snow and ice and moving it rearwardly in the machine, whereby frictional heat and triturators therein will cause the snow and ice to melt or be converted into water, the water so formed being emptied in the front of the machine to facilitate the removal of the remaining snow and ice from the street.

Still another object of the invention is to provide a snow-removal machine which includes a novel mechanism for gathering, breaking and melting the snow and ice, the machine being simple and inexpensive to operate.

Other objects and advantages will become apparent during the course of the following description.

In the accompanying drawings forming a part of this application, and in which like numerals are used to designate like parts throughout the same:

Figure 1 is a side elevational view of the snow-removal machine constructed according to the present invention;

Figure 2 is a fragmentary top plan view of the snow-removal machine of the present invention;

Figure 3 is an enlarged horizontal sectional view of the snow-removal machine;

Figure 4 is a sectional view taken on the line 4—4 of Figure 3;

Figure 5 is a transverse vertical sectional view taken through the front end of the snow-removal machine;

Figure 6 is a sectional view taken on the line 6—6 of Figure 4;

Figure 7 is a sectional view taken on the line 7—7 of Figure 4;

Figure 8 is a sectional view taken on the line 8—8 of Figure 4;

Figure 9 is a longitudinal horizontal sectional view taken through one of the triturators;

Figure 10 is a fragmentary top plan view of a modified feed screw;

Figure 11 is an end elevational view of the feed screw of Figure 10.

Referring in detail to Figures 1 through 9 of the drawings, there is shown a snow-removal machine which is adapted to travel along a snow-covered road or street by the latter.

2

The snow-removal machine or apparatus includes a horizontally disposed base 20 that supports thereon a hollow housing 21, the housing 21 being secured to the base 20 in any suitable manner. A pair of small front wheels 22 support the front end of the machine, there being a pair of larger wheels 23 supporting the rear end of the machine. An axle 24 extends between the pair of rear wheels 23. The axle 24 is caused to rotate by an engine 4, whereby the machine will be propelled along a road.

Projecting from the rear end of the base 20 and secured thereto is a platform 3 which is adapted to support the engine 4 thereon. A shaft 5 connects the engine 4 to a conventional transmission 6, there being a chain 7 for operatively connecting shaft 5 to a second transmission 8. The second transmission 8 serves to actuate a rear axle differential 9, the differential 9 being connected to the rear axle 24. The first transmission 6 is operatively connected to a drive shaft 101 for a purpose to be later described. For steering the snow-removal machine, rods 26 extend longitudinally along the machine, and rods 26 can be moved to thereby swing links 27 so that front wheels 22 can be pivoted or turned to the desired direction.

A cover 28 of arcuate formation is detachably connected to housing 21 by suitable securing elements, such as bolt-and-nut assemblies 29, and cover 28 can be removed when it is desired to gain access to the mechanism within the housing 21. The front end of housing 21 has projecting therefrom a downwardly inclined shovel 30 which serves to scoop up snow and ice as the snow machine is moved along the road or street. The front of housing 21 is also provided with an enlarged frame 31 and supported by the lower end of frame 31 is a horizontally disposed rotary cutter 32. Cutter 32 serves to chop or break up frozen ice and snow as the machine is being operated, Figure 5. Cutter 32 includes a shaft 33 that has a sleeve 34 mounted thereon. The sleeve 34 is provided with a plurality of spiral fins 35 which serve to move the ice and snow toward the center of the machine. The fins 35 are provided with a plurality of spaced projecting teeth 36 which serve to chop up or break the ice as the cutter 32 is rotated. The mechanism for rotating the cutter 32 is described later in this application.

Arranged in spaced parallel relation above the cutter 32 is a pair of horizontally disposed screw members 37 and 38. The screw members 37 and 38, when rotated, serve to urge snow or ice that may be piled up in front of the machine toward the middle of the machine and through a semi-circular opening 39 in a plate 40 that extends across the front of the housing 21. The screw member 37 includes a shaft 42 which is rotatably supported by the side portions of the frame 31,

and mounted on the shaft 42 is a pair of cylindrical sleeves 43 and 44, Figure 5. A spiral-shaped blade 45 is secured to the sleeve 43, and a similar blade 46 is secured to the other sleeve 44. The other screw member 38 includes a shaft 47 that is rotatably supported by the frame 31, and mounted on the shaft 47 is a pair of cylindrical sleeves 48 and 49. A spiral-shaped blade 50 is secured to the sleeve 48, while a similar blade 51 is secured to the other sleeve 49. The shape of these blades is such that upon rotation of the screw members 37 and 38 the snow or ice will be urged toward the center of the machine and through the openings 39.

Extending longitudinally through the housing 21 is a horizontally disposed driven shaft 52, the rear end of the driven shaft 52 extending through a vertically disposed back wall 53 that serves to close the rear end of the housing 21. Suitable bearings are provided, or arranged, along the driven shaft 52 so as to insure the proper rotation thereof. Mounted on the driven shaft 52 adjacent the front end thereof is a feed screw 54 which is adapted to pick up or receive the snow and ice that enters through the opening 39, the feed screw 54 serving to move the snow and ice rearwardly in the housing 21. The feed screw 54 is provided with fins or blades 55 that project outwardly therefrom, Figure 4. The feed screw 54 is keyed or otherwise connected to the driven shaft 52 so that as the driven shaft 52 rotates, the feed screw 54 will rotate therewith, the feed screw 54 normally turning at a relatively slow rate of speed.

A mechanism is provided for coating with the feed screw 54 to help move the snow and ice rearwardly in the machine, and this mechanism, to be described, also helps chop up and break up the snow and ice. This mechanism includes a shaft 56 which is arranged above the cover 28, and secured to the shaft 56 is a pair of ears or blades 57 and 58. The blades or ears 57 and 58 are turned in a counterclockwise direction, Figure 4, and for causing this turning movement a short shaft 59 has a bevel gear 60 mounted on its rear end, and the bevel gear 60 meshes with a bevel gear 61 that is secured to the shaft 56. A bevel gear 62 is arranged on the front end of the shaft 59, and a bevel gear 63 is arranged in meshing engagement with the bevel gear 62. The bevel gear 63 is arranged on the upper end of a vertically disposed shaft 64, there being a similar bevel gear 65 arranged on the lower end of the shaft 64. The bevel gear 65 meshes with a bevel gear 66 that is mounted on the front end of the driven shaft 52, so that rotation of the driven shaft 52 causes the ears 57 and 58 to rotate and help break up and move the snow and ice rearwardly in the housing. The blades 57 and 58 are so arranged that they will not interfere with the rotation of the feed screw 54, and also the blades 57 and 58 are surrounded by a closure member 67.

The rotation of the driven shaft 52 also serves to drive or rotate the screw members 37 and 38 and the rotary cutter 32. For accomplishing this rotation of these members, a horizontally disposed shaft 68 has a bevel gear 19 on its inner end, the bevel gear 19 being arranged in meshing engagement with the bevel gear 66 on the front end of the driven shaft 52. The other end of the shaft 68 serves to operate a conventional chain-and-sprocket mechanism 69, and the chain-and-sprocket mechanism 69 is also operatively connected to one end of each of the shafts 70

42 and 47 for rotating the screw members 37 and 38. A chain-and-sprocket mechanism 70 serves to connect one end of the shaft 47, whereby rotation of the driven shaft 52 causes the screw members 37 and 38 to rotate and also causes the cutter 32 to rotate.

Arranged rearwardly of the feed screw 54 and rotatably or loosely mounted on the driven shaft 52 is a drum 71. The drum 71 has an inclined or tapered front portion 72, and projecting from the rear end of the drum 71 is a collar 73 which has a gear wheel 74 secured thereto for a purpose to be later described. Secured to the tapered portion 72 of the drum 71 are blades 75, and these blades 75 tend to urge the snow or ice rearwardly in the housing 21 and these blades also move the snow and ice against the inner surface of the housing 21 and cover 28. As the snow and ice are thus moved, it is subjected to frictional heat, whereby the snow and ice will start to be melted or converted into water.

A means is provided for generating additional frictional heat in the snow and ice that has been scooped up, and this means also serves to convey the snow and ice to a pair of triturators, as later described. This means comprises an annular L-shaped bracket 76 which is secured to the drum 71, and secured to the exterior surface of the bracket 76 are curved ribs 77 which serve to move the snow and ice toward the back wall 53 as the drum 71 is rotated. A second bracket 79 is arranged in spaced parallel relation with respect to the bracket 76, and the bracket 79 is secured to a stationary brace 78, the brace 78 being connected to the housing 21 in any suitable manner. Secured to the inner surface of the bracket 76 is an arcuate rib 80, while secured to the outer rear portion of the drum 71 is a further arcuate rib or blade 81. Arranged between the brace 78 and the back wall 53 is a trough 82 which has a semi-circular formation. Thus, it will be seen that as the drum 71 is rotated, the blade 75 will receive the snow and ice from the feed screw 54 and then the snow and ice will be urged against the inner surface of the housing, so that the snow and ice will start to melt. Then, the snow and ice which may be partly melted is moved rearwardly by the rotating rib 77, whereupon additional frictional heat is created and then the partially melted snow and ice is carried forwardly by the rib 80, so that the partially melted snow and ice passes through the space between the brackets 76 and 79. Next, the snow and ice or slush is conveyed forwardly by the rib 81 which is secured to the drum 71, so that the snow and ice passes forwardly again through the space between the bracket 79 and the drum 71, and then the material enters or is received in the trough 82, Figure 4. Further, the revolving drum 71 is turning at a relatively fast rate of speed, so that by action of centrifugal force the snow and ice will be thrown against the housing or cover, whereby additional heat will be provided for helping to melt this material. For helping to free or remove any ice or snow that may tend to clog up the rear portions of the machine, a pair of scrapers 83 and 84 each have their inner end secured to the rear end of the drum 71 by suitable securing elements, such as screws 85.

Extending longitudinally through the housing 21 is a pair of spaced parallel, horizontally disposed triturators which are designated generally by the numerals 86 and 87. Each of these triturators has the same construction, and each of the triturators has its rear end open, as best seen

in Figure 9, for communication with the trough 82. In other words, by the time the material or snow and ice reaches the rear open ends of the triturators 86 and 87, the snow and ice is practically all water, and the triturators serve to convey this water forwardly where the water is dispensed immediately in front of the snow-removal machine so as to facilitate the removal of the remaining snow and also to help wash down the streets. However, if any snow or ice is carried into the triturators, the snow and ice will be melted by frictional heat or centrifugal force generated therein. Since each of the triturators 86 and 87 has the same construction, only one will be described in detail. Thus, the triturator 86 includes a body member 93 which coacts with the housing 21 to define a tube for the passage therethrough of the fluid or melted snow and ice. The triturator further includes a shaft 88 which has a cylinder 89 mounted thereon, and secured to the outer surface of the cylinder 89 is a spiral-shaped blade or fin 90 which urges the slush or water forwardly as the cylinder 89 is rotated. Mounted on the rear end of the shaft 88 is a bevel gear 91, and a plurality of spaced openings 92 are arranged in the front of the triturator 86 for the egress therethrough of water that is dispensed in front of the snow-removal machine. The other triturator 87 has a shaft 94 which serves the same purpose as the shaft 88, and mounted on the rear end of the shaft 94 is a bevel gear 95.

Projecting upwardly from the rear end of the base 20 and secured thereto is a vertically disposed plate 96. The plate 96 coacts with the back wall 53 and with a pair of vertically disposed, spaced parallel side walls 97 and 98 to define a casing 99, and the casing 99 incloses the mechanism for operatively driving the triturators, driven shafts, and drum, there being a lid 100 normally closing the casing 99.

Projecting rearwardly from the casing 99 is a drive shaft 101, and the drive shaft 101 is operatively connected to the transmission 6. Arranged within the casing 99 and mounted on the drive shaft 101 is a worm 102, and also mounted on the inner end of the drive shaft 101 is a gear wheel 103 for a purpose to be later described. The gear wheel 103 meshes with an idler gear 104 that is supported by a straight shaft 105, and the idler gear 104 meshes with the gear wheel 74 that is secured to the drum 71. Thus, as the drive shaft 101 rotates, the drum 71 will be rotated therewith.

Extending between the side walls 97 and 98 and rotatably supported thereby is a first horizontally disposed stud shaft 106 which has a worm gear 107 mounted thereon. The worm 102 on the drive shaft 101 is arranged in meshing engagement with the worm gear 107, so that rotation of the drive shaft 101 causes rotation of the stud shaft 106. Arranged in spaced parallel relation below the first stud shaft 106 is a second stud shaft 108, and a gear wheel 109 is mounted on the stud shaft 108. A similar gear wheel 110 is mounted on the first stud shaft 106, the gear wheels 109 and 110 being arranged in meshing engagement with each other, whereby rotation of the stud shaft 106 causes rotation of the stud shaft 108. Mounted on the second stud shaft 108 adjacent the outer end thereof is a pair of bevel gears 111 and 112. The bevel gear 111 meshes with the bevel gear 91 of the triturator 86, while the other bevel gear 112 meshes with the bevel gear 95 on the triturator 87, so

that this rotation of the stud shaft 108 results in the actuation of the triturators 86 and 87.

Arranged in spaced parallel relation above the stud shaft 106 is a short, horizontally disposed shaft 113, Figure 7. Mounted on the shaft 113 intermediate its ends is a gear wheel 114 which meshes with a gear wheel 115 that is mounted on the stud shaft 106. Thus, rotation of the stud shaft 106 causes the shaft 113 to also rotate. Mounted on the inner end of the shaft 113 is a bevel gear 116 which is arranged in meshing engagement with a bevel gear 117, and the bevel gear 117 is mounted on the rear end of the driven shaft 52. It is to be noted that the gear wheel 74 is loosely or rotatably mounted on the driven shaft 52, so that the feed screw 54 and drum 71 are rotated independently of each other.

Referring in detail to Figures 10 and 11 of the drawings, there is shown a modified feed screw 118 which may be used in lieu of feed screw 54. The feed screw 118 includes a hollow sleeve 119 that is adapted to be arranged in surrounding relation with respect to the front end of the driven shaft 52 and secured thereto by means of suitable securing elements which may be projected through the openings 121. Projecting from the sleeve 119 is a plurality of spaced rods 120 which are adapted to urge the snow and ice rearwardly in the housing of the machine when the machine is being operated.

Suitable horizontally disposed brace rods 122 extend along the snow-removal machine for helping to maintain the parts in assembled relation and the number of these rods may be varied as required.

In use, the snow-melting machine of the present invention is caused to move or travel by means of the engine 4. Then, as the snow-melting machine moves along the snow and ice-laden street, the snow and ice will be effectively removed and collected from the street. This is accomplished as follows:

The drive shaft 101 is operatively connected to the engine 4 through the transmission 6, and rotation of the drive shaft 101 causes rotation of the driven shaft 52 in a counterclockwise direction by means of the previously-described structure, the engine 4 also serving to propel the machine forwardly. As the driven shaft 52 rotates, the shaft 68 is also rotated, and this results in rotation of the screw members 37 and 38, whereby any snow or ice that is piled up in front of the machine will be directed toward the center thereof and through the opening or hole 39. Simultaneously, the rotary cutter 32 is turned by means of the sprocket mechanism 70, and the shovel 30 will collect or scoop up the snow and ice from the ground. The snow and ice then pass through the opening 39 and onto the feed screw 54. Since the feed screw 54 is keyed or otherwise connected to the driven shaft 52, the snow and ice will be conveyed rearwardly in the machine. The blades 57 and 58 are also rotating, and these blades help to chop up the snow and ice and also tend to urge the snow and ice rearwardly in the housing. The snow and ice is next discharged from the feed screw 54 onto the drum 71, whereby the blades 75 begin to urge the snow and ice against the inner walls of the housing and cover, whereby frictional heat is generated so that the snow and ice are partially converted or melted into water. This mixture of snow, ice and water then is forced rearwardly by the rib 77, Figure 4, and then the mixture of material is moved forwardly between

the brackets 19 and 76 by the rib 80, and then the mixture is again moved forwardly between the drum 11 and the stationary bracket 78 by means of the rib 81. As the snow and ice or slush follow this circuitous or tortuous path, additional frictional heat is generated, whereby there is produced or formed a high percentage of water. The fluid mixture then passes, or is received in the trough 82 and the trough 82 has communicating therewith the rear ends of the pair of triturators 86 and 87. Each of the triturators 86 and 87 has the revolving cylinders provided with spiral blades thereon so that the fluid mixture is conveyed forwardly in the machine. The triturators 86 and 87 serve to convert any remaining ice and snow into water by the combination of frictional heat and centrifugal force, and the water so formed is dispensed through the openings 92 and out of the front of the machine, whereby this water helps to facilitate the removal of the remaining snow and ice from the streets, and this water also helps wash down the streets.

From the foregoing, it is apparent that a snow-melting machine has been provided, wherein snow and ice can be readily removed from the streets without the necessity of burning oil or using fuel to provide heat for melting the ice. The ice and snow are entirely melted by the combination of frictional heat and centrifugal action, as previously described. Thus, the machine can be operated to remove snow and ice from the streets of municipalities and the like with a high amount of economy. The blades on the screw members 37 and 38 urge the snow and ice toward the center of the machine, and the feed screw 54 urges the snow and ice rearwardly. The drum 11 turns in the opposite direction from the driven shaft 52. The pair of triturators are operated or rotated by means of the bevel gears 111 and 112 which are mounted on the stud shaft 108, the stud shaft 108 being rotated through the intermeshing gears 109 and 110. The drum 11 is driven at a relatively high speed in a direction opposite to the feed screw 54, and this results in the snow and ice being caused to start to melt the latter.

I claim:

1. In a snow-removal machine, a horizontally disposed base, a pair of spaced parallel vertically disposed side walls projecting upwardly from the rear end of said base and secured thereto, a hollow housing supported on said base, an arcuate cover detachably connected to said housing, a vertically disposed back wall for closing the rear end of said housing, an inclined shovel projecting downwardly from the front end of said housing, a vertically disposed plate arranged in spaced parallel relation with respect to said back wall and coacting with said back wall, base and side walls to define a casing, a horizontally disposed rotary snow and ice cutter arranged above said shovel, a pair of horizontally disposed spaced parallel screw members arranged above said ice cutter, a driven shaft extending longitudinally through said housing, a feed screw mounted on said driven shaft for rotation therewith, a drum arranged rearwardly of said feed screw and rotatably mounted on said driven shaft, a plurality of ribs and blades mounted on said drum, a pair of spaced parallel horizontally disposed triturators extending longitudinally through said housing, means for directing the material onto said triturators, and means in said casing for rotating said driven shaft, drum and triturators.

2. A snow-removal machine comprising a horizontally disposed base, ground-engaging wheels for supporting said base, a hollow housing supported on said base and secured thereto, a cover detachably connected to said housing, said housing having its front end terminating in an enlarged frame, an inclined shovel projecting from the lower front end of said housing, a horizontally disposed rotary cutter supported by said frame and arranged contiguous to said shovel, a pair of spaced parallel horizontally disposed screw members rotatably supported by said frame, a horizontally disposed driven shaft extending longitudinally through said housing, a feed screw arranged in said housing adjacent the front thereof and connected to said driven shaft, means operatively connecting said driven shaft to said screw members and rotary cutter, a drum arranged rearwardly of said feed screw and rotatably mounted on said driven shaft, fins and blades secured to the exterior of said drum, a pair of spaced parallel horizontally disposed triturators arranged in said housing, means for conveying the material from said drum to said triturators, a casing arranged on the rear end of said base, a drive shaft extending rearwardly from said casing and adapted to be connected to an engine, and means in said casing operatively connecting said drive shaft to said driven shaft, and to said drum.

3. The apparatus as described in claim 2, and further including a means in said casing for operatively connecting said drive shaft to said triturators.

4. In a snow removal machine, a base, a pair of side walls projecting upwardly from said base and secured thereto, a hollow housing supported on said base, a cover detachably connected to said housing, a back wall for closing the rear end of said housing, an inclined shovel projecting downwardly from the front end of said housing, a plate arranged in spaced parallel relation with respect to said back wall and coacting with said back wall, base and side walls to define a casing, a horizontally disposed rotary snow and ice cutter arranged above said shovel, a pair of horizontally disposed spaced parallel screw members arranged above said ice cutter, a driven shaft extending longitudinally through said housing, a feed screw mounted on said driven shaft for rotation therewith, a drum arranged rearwardly of said feed screw and rotatably mounted on said driven shaft, a plurality of ribs and blades mounted on said drum, a pair of spaced parallel horizontally disposed triturators extending longitudinally through said housing, means for directing the material onto said triturators, and means in said casing for rotating said driven shaft, drum and triturators.

FRANK M. BECKER.
